COMBINED PHONOGRAPH, RADIO AND TELEVISION CABINET

Frank M. Freimann and Clyde L. Welbaum, Fort Wayne,
Ind., assignors to The Magnavox Company, Fort
Wayne, Ind., a corporation

Filed Sept. 15, 1960, Ser. No. 62,142

Term of patent 14 years

(Cl. D56—4)

Fig. 1.

Fig. 2.

Fig. 3.

Fig. 4

FIG. 1 is a front view of a combined phonograph, radio and television cabinet showing our new design;

FIG. 2 is a top plan view;

FIG. 3 is a front view illustrating the doors in open position; and

FIG. 4 is a side elevational view thereof.

Both sides of the cabinet have an appearance as shown in FIG. 4. The rear of the cabinet is without ornamentation.

We claim:

The ornamental design for a combined phonograph, radio and television cabinet, as shown and described.
